KEY

John F. Henshaw, San Francisco, Calif., assignor to
Schlage Lock Company, a corporation

Application September 25, 1958, Serial No. 52,759

Term of patent 14 years

(Cl. D50—4)

Fig. 1 is a perspective of a key showing my new design.

Fig. 2 is a front elevation of the key.

Fig. 3 is a rear elevation of the key.

Fig. 4 is an edge elevation of the key.

Fig. 5 is a bottom plan view of the key of Fig. 2.

Fig. 6 is a top plan view of the key of Fig. 2.

The dominant feature of the design resides in the solid line portion.

I claim:

The ornamental design for a key, as shown and described.
